UNITED STATES PATENT OFFICE.

FRANCIS V. ROBERTS, OF LOS ANGELES, CALIFORNIA.

SHOE-POLISHING APPLIANCE.

Application filed November 4, 1921. Serial No. 512,877.

To all whom it may concern:

Be it known that I, FRANCIS V. ROBERTS, a citizen of the United States, residing at Los Angeles, in the county of Los Angeles and State of California, have invented new and useful Improvements in Shoe-Polishing Appliances, of which the following is a specification.

This invention relates to shoe polishing appliances and has for its primary object to provide an adjustable appliance particularly adapted for holding shoes not worn and so constructed as to readily support a shoe or the like to be polished immaterial 15 of the size of the said shoe.

Another object of this invention is to provide means for readily folding the appliance against a wall or other suitable support when the said appliance is not in use.

20 A further object of this invention is to provide means associated with the appliance for quickly and easily retaining in a fixed position the heel and sole of the shoe to be polished.

25 A still further object of this invention is to provide a device of the character described which is simple in construction, economical to manufacture, positive in operation, and a device which can be readily assembled and disassembled when occasion may demand.

Other objects and advantages will be apparent during the course of the following description.

In the accompanying drawings forming a part of this specification, and in which like numerals are employed to designate like parts throughout the same,

Fig. 1 is a side elevation of a boot black appliance embodying my invention, showing 40 a shoe to be shined in position on the appliance,

Fig. 2 is a top plan view of the same with the shoe removed therefrom,

Fig. 3 is a section through the sole holding mechanism the view being taken on the line 3—3 of Figure 2,

Fig. 4 is a bottom plan view of the same, and

Fig. 5 is a transverse vertical section 50 through the same, the view being taken on the line 5—5 of Figure 2.

In the accompanying drawings wherein for the purpose of illustration is shown a preferred embodiment of my invention, the 55 reference character "A" indicates a shoe to be polished shown in position on the appli-

ance, while the symbol B designates a suitable support such as a wall to which the appliance is detachably secured.

As shown to advantage in Figure 1 the 60 appliance embodies in its construction upper and lower brackets 6 and 7, respectively. These brackets are detachably secured to the wall "B", by fastening elements 8. To the brackets 6 there are pivotally secured the 65 extremities 9 of a pair of serrated arms 10, which are bent at right angles and extended to form a rectangular frame 11. Connected to the sides of the frame are depending flanges 12 of a top plate 13. In the plate 70 13 there are provided a pair of transverse slots 14 in which are received rivets 15 adapted to act in conjunction with the slots for guiding a pair of toe clamps 16 therein. These clamps terminate at their respective 75 outer ends in up-struck lips 17 adapted to engage the sides of the shoe "A" and are serrated on their respective inner edges as at 17'.

It will be evident from this construction 80 that the clamps are constructed to move laterally, and the mechanism for controlling the lateral movements of the clamps includes a worm shaft 18 which lies in a plane parallel to the plane of the top plate 13. The worm 85 shaft has its extremities receivable in flanges 12 of the said plate and also the sides of the frame 11. On one of the extremities there is formed a key-receiving portion 19, the purpose of which will be hereinafter explained.

Adapted to penetrate the top plate and to lie in a plane at right angles to the plane of the worm shaft 18, is a vertically disposed short shaft 20 which has mounted on its 95 upper extremity a gear 21 and on its lower extremity a second gear 22 of a greater diameter than the gear 21. These two gears are fixedly engaged with the shaft 20 and accordingly rotatable therewith. Thus, 100 when the worm shaft is actuated by the appliance of a key to the portion 19, the lower gear meshing with the worm shaft 20 will be actuated thereby and a rotatable motion will be imparted to the upper gear 21. 105 Since the last mentioned gear is in mesh with the teeth of the toe clamp 16, it will be further obvious that the above mentioned lateral movement will be imparted to the respective toe clamps. This mechanism is devised for readily retaining and releasing the sole of the shoe, and from its construction 110

it will be evident that it can be adjusted to fit various widths of shoes.

For the purpose of retaining the heel of the shoe I propose to straddle the arms 10 with a spring heel clamp which is so formed as to snugly engage the sides of the arm 10. This clamp has integrally formed therewith an upwardly positioned extension 24 for engaging the front of the heel of the shoe and 10 a downwardly inclined lug 25 adapted to engage the teeth of the arms 10.

By referring to Figures 1 and 2 it will be evident that the appliance can be readily collapsed from its normally extended position 15 to an inoperative position. In order to accomplish this result, I propose to pivot to the lower bracket 7 one end of an arm 26 and to pivot to the arms 10 adjacent the frame 11 a pair of arms 27. The pair of arms 27 are 20 hingedly connected to the arm 26, as at 28. A pair of stops 29 are integrally formed with the arm 26 and are adapted to engage the inner edges of the arms 27 so as to limit the degree of extension of the respective 25 arms when the appliance is in the position shown to advantage in Fig. 1. When it is desired to return the appliance to an inactive position the respective parts of the appliance will assume the dotted line position, 30 as shown in Figure 1. It will be obvious from this construction that the appliance can

be readily moved to a position to receive the shoe for the purpose of shining the same, particularly when the shoe is not being worn, or on the other hand can be readily folded 35 so that the appliance will be positioned parallel to the support B, and will accordingly occupy but a minimum amount of space.

Having thus described my invention, I claim:

In a device of the character described, the combination with a support, of a pair of brackets secured to said support, serrated arms pivoted to one of said brackets, a heel retaining clamp slidable on said serrated 45 arms, means for preventing free movement of said clamp in one direction, laterally movable sole engaging clamps mounted on the extremity of said serrated arms, means for moving said clamps, a plurality of pivoted 50 arms disposed between the other of said brackets and the extremities of said serrated arms and adapted to permit said device to be collapsed from a position extending outwardly from said support to a position 55 adjacent said support, and stops on one of said pivoted arms adapted to engage the other of said arms for the purpose of limiting the movement of said pivoted arms in one direction.

In testimony whereof I affix my signature.

FRANCIS V. ROBERTS.
